CLAIM

The ornamental designs for furniture for hairdressers, as shown and described.

DESCRIPTION

FIG. 1 is a front/top perspective view of my furniture for hairdressers;

FIG. 2 is a front view of the first embodiment thereof;

FIG. 3 is a left side view of the first embodiment thereof;

FIG. 4 is a right side view of the first embodiment thereof; and,

FIG. 5 is a top view of the first embodiment thereof.

The broken lines in the figures are for the purpose of illustrating environmental features that form no part of the claimed design.
